Dec. 309

Robert Donavan of Pittsburg Pa.
Letters Patent. No. 309. Dated August 20. 1850.

The Schedule referred to in these Letters Patent and making part of the same.

So all whom it may concern:

Be it known that I Robert Donavan
of Pittsburg in the County of Allegheny and Commonwealth of Pennsylvania have invented
or produced a new design for the plates of Cooking Stoves, and I do hereby declare that the
following is a full and exact description of the same, reference being had to the annexed draw-

ing which represents one half of the front plate of a Cooking Stove and one of the front doors.

The device or designs which I desire to secure by Letters Patent can be fully comprehended only by reference to the accompanying drawing which I therefore desire to form a part of this Specification. The outer edge of the door is surrounded by a raised moulding or bead, the door being a rectangular oblong. This moulding circumscribes a raised surface in the shape of an oblong figure with straight parallel sides and semicircular ends. On the surface of this raised figure on the door is a device composed of a symmetrical arrangement of scallops & diamonds & reticulated figures, as exhibited in the drawing.

The device on the plate of the stove is a repetition of an oblong figure surrounded by a single bead or moulding which forms an oblong rectangular figure with the corners cut off. The figure inside the moulding is an intaglio impression of a hemisphere surrounded by a star with six points, from opposite sides of this star proceed two stems, each stem bearing two leaves and a flower with four petals, also in intaglio. These devices are enclosed by four scrolls, one on each side & one at each end.

What I claim as my invention and desire to secure by Letters Patent is the ornamental design for stove plates as herein described & which is fully set forth in the drawing accompanying this description.

Witnesses.
